C. R. BEALL

SPEED RESPONSIVE SYSTEM

Filed Sept. 5, 1923

INVENTOR:

C. R. Beall,

His Attorney

UNITED STATES PATENT OFFICE.

CHARLES R. BEALL, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

SPEED-RESPONSIVE SYSTEM.

Application filed September 5, 1923. Serial No. 661,026.

My invention relates to railway traffic controlling apparatus, and particularly to apparatus of the type wherein a train is provided with governing mechanism controlled 5 in part by the speed of the train.

In at least one arrangement of apparatus of such type which has been suggested, a speed responsive device is operated by a shaft which is caused to rotate at a definite 10 speed for each speed of the train. One form of apparatus which operates in this manner is illustrated and described in an application for United States Letters Patent filed on even date herewith by L. O. Grondahl, Serial No. 661,036, filed on the 5th day of September, 1923, Pat. No. 1,581,113, Apr. 20, 1926, for railway traffic controlling apparatus. One feature of my invention is the provision of means for checking the fact 20 that the shaft is rotating at the proper speed for each value of train speed.

I will describe one form and arrangement of apparatus embodying my invention, and will then point out the novel features thereof 25 in claims.

The accompanying drawing is a diagrammatic view showing one form of apparatus embodying my invention.

Referring to the drawing, the reference 30 character A designates an axle of a train, and the reference character B designates a shaft which is caused to rotate at a definite speed for each speed of the axle by means not essential to the complete disclosure of my invention and omitted from the drawing for the sake of simplicity. One means for accomplishing this is disclosed in United States Letters Patent No. 1,508,554 granted to Lemuel F. Howard on 35 Sept. 16, 1924. The reference character C designates a valve comprising a chamber 2 one wall of which is provided with a valve seat 3 which is at times engaged by a closing member 4 operated by a solenoid D. When 40 this solenoid is energized, that is, when an electric current is passing through coil 6, core 5 is drawn upward and causes member 4 to abut against seat 3 thus closing the valve C. When solenoid D is de-energized, 45 member 4 drops down under the influence of gravity, and opens valve C to atmosphere. The brakes of the vehicle are governed in any suitable manner so that when the fluid normally under pressure in pipe 1 is re-

leased to the atmosphere, the brakes of the 55 vehicles are applied. The energization of solenoid D is controlled in part by a polarized relay E which is in turn controlled by traffic conditions in advance in such manner that under conditions permitting high 60 speed, contact 7-10 is closed; under conditions permitting an intermediate speed but not high speed, contact 7-8 is closed; and under conditions requiring low speed, contact 7-9 is closed. 65

Mounted upon shaft B and rotating therewith is a centrifugal device X which comprises, as shown in the drawing, a collar 16 rigidly attached to shaft B. Two weights 20 are operably connected to this collar by 70 means of links 19. In similar manner these weights are also fastened to a second collar 18 slidably mounted on shaft B. When this device is rotated the centrifugal force generated by virtue of the motion of the 75 weights 20, tends to move the second collar 18 longitudinally toward the right along shaft B against the biasing force exerted by a spring 17. A contact mechanism F is operated by this centrifuge and comprises 80 a movable contact member 14 which co-operates with three fixed contact members 13, 12 and 11. The movable member 14 is operated by the collar 18 of centrifugal device X in such a manner that as the speed of 85 shaft B increases, member 14 is moved toward the right. The fixed contact members 13, 12 and 11 are so proportioned and so disposed that at speeds of the vehicle above some high speed, as 65 miles per hour, the 90 movable member 14 does not engage any of the fixed contact members; at all speeds below 65 miles per hour, member 14 engages member 11; at all speeds below some intermediate speed as 35 miles per hour, member 14 engages both members 11 and 12; and at all speeds below some low speed, as 95 15 miles per hour, member 14 engages all three fixed contacts 11, 12 and 13.

The reference character M designates apparatus comprising two groups of oppositely disposed contacts 48 and 49, each contact in one group being connected with the opposite contact in the other group by means of a conductor 50. A movable brush 46 is operated by the collar 18 of the centrifugal device X in such manner that as the speed of shaft B increases, brush 46 is moved up- 100 105

- wardly. A similar brush 47 is controlled by a similar centrifugal device J on axle A so that as the speed of the axle increases the brush 47 is also moved upwardly. It is evident that the amount of this motion may be made equal for corresponding increases in speed of the axle and shaft so that when the speed of shaft B corresponds to the speed of axle A the brushes 47 and 46 are electrically connected by two oppositely disposed contacts 48 and 49 and the associated conductor 50. The circuit for winding 6 of valve solenoid D passes from generator G through the contacts of relay E and speed responsive device F, wire 45, brush 46, a contact 49, the associated conductor 50 and contact 48, brush 47, wire 44, winding 6, and wire 43 to the generator G. If the speed of shaft B is greater or less than the proper value corresponding to the speed of axle A, the two brushes 46 and 47 will suffer relative displacement which will interrupt the circuit for winding 6 and will allow valve C to open and apply the brakes. The amount of deviation from absolutely correct relative speeds of shaft B and axle A before such brake application will occur may be regulated by proper dimensioning of brushes 46 and 47, contacts 48 and 49 and the centrifugal devices X and J.
- Although I have herein shown and described only two forms of railway traffic controlling apparatus embodying my invention, it is understood that various changes and modifications may be made therein within the scope of the appended claims without departing from the spirit and scope of my invention.
- Having thus described my invention, what I claim is:
1. In combination, an axle, a first centrifugal device operated by said axle, a shaft operated at a definite speed for each speed of said axle, a second centrifugal device operated by said shaft, an electro-responsive device, and means controlled by said first and said second centrifuges for effectively energizing said device only when said shaft and said axle are operating at proper relative speeds. 50
2. In combination, an axle, a first centrifugal device operated by said axle, a shaft operated at a definite speed for each speed of said axle, a second centrifugal device operated by said shaft, a brush operated by said first centrifugal device, a second brush operated by said second centrifugal device, and means for electrically connecting said first brush with said second brush only when said shaft and said axle are operating at proper relative speeds. 55
3. In combination, an axle, a first centrifugal device operated by said axle, a shaft operated at a definite speed for each speed of said axle, a second centrifugal device operated by said shaft, two series of oppositely disposed contacts each contact in one series being connected electrically with the opposite contact in the other series, a brush operated by said first centrifugal device for successively engaging the contacts in one of said series as the speed of said axle increases, a second brush operated by said second centrifuge for successively engaging the contacts in the other of said series, the two said 70 brushes engaging opposite contacts in the two said series when the speed of said axle and said shaft have the proper relative values. 75
4. In an electric circuit controlling mechanism, the combination with two rotating elements, of a plurality of contact segments associated with one element, contact segments associated with the other element and electrically connected to corresponding contact segments of the first element, and a contact member engaging a corresponding connected segment of each element to continuously maintain an electric circuit closed so long as both elements rotate in synchronism. 80
- In testimony whereof I affix my signature. 85
- CHARLES R. BEALL. 90
